(57) **CLAIM**

The ornamental design for an eyeglass retainer, as shown and described.

DESCRIPTION

FIG. 1 is an isometric view of the eyeglass retainer shown in use;

FIG. 2 is a front view of the eyeglass retainer;

FIG. 3 is a rear view of the eyeglass retainer;

FIG. 4 is a left view of the eyeglass retainer, right view mirror thereof;

FIG. 5 is a top view of the eyeglass retainer; and

FIG. 6 is a bottom view of the eyeglass retainer; and,

FIG. 7 is a detail view of FIG. 4.

The broken lines shown in the drawings illustrate portions of the eyeglass retainer that form no part of the claimed design.

1 Claim, 6 Drawing Sheets
